UNITED STATES PATENT OFFICE.

JOSEPH T. BROGDEN, OF PROVIDENCE, RHODE ISLAND, ASSIGNOR TO REVERE RUBBER COMPANY, A CORPORATION OF RHODE ISLAND.

WIND-UP DEVICE FOR SHEETED MATERIAL.

1,327,420.

Specification of Letters Patent.

Patented Jan. 6, 1920.

Application filed July 25, 1916. Serial No. 111,121.

To all whom it may concern:

Be it known that I, JOSEPH T. BROGDEN, a citizen of the United States, residing at Providence, in the county of Providence and State of Rhode Island, have invented 5 certain new and useful Improvements in Wind-Up Devices for Sheeted Material, of which the following is a full, clear, and exact description.

10 This invention relates to devices for winding up sheeted material and has for an object to provide a device of this character which will wind up sheeted rubberized material which has been chalked without subjecting the same to harmful pressure.

15 In the manufacture of rubberized fabric, after being treated with rubber, the fabric is coated with chalk or an equivalent, and is then wound up in a roll, the chalk serving 20 to keep the rubber surfaces of the convolutions from sticking together. It is desirable that the fabric be smoothly and evenly wound up, and ordinarily to accomplish this, a constant tension is maintained on the 25 fabric. This tension causes an increase in the pressure of the outer convolutions against the inner convolutions as the roll of fabric increases in diameter, and this is an objectionable feature, for when the pressure 30 becomes too great, the chalk will be squeezed away in places, or at least harmfully thinned out, and let the rubber surfaces contact and adhere together.

35 To overcome this disadvantage, the present invention provides a wind-up device in which the roll of material is wound up by frictional contact with a revolving roller, the weight of the fabric roll upon the driving roller being utilized to supply sufficient 40 pressure to smooth out the fabric web during the winding operation. As the fabric roll increases in diameter, provision is made for a corresponding movement of the axis of the roll away from the driving roller, 45 so that the pressure of the outer convolutions against the inner convolutions will always remain substantially the same regardless of the diameter of the roll. Therefore at no time can a sufficient degree of pressure be 50 reached to squeeze out the chalk from between the convolutions.

The invention can be readily understood from the following description taken in con-

nection with the accompanying drawing, in which—

55 Figure 1 is a plan view of the apparatus embodying my improvements.

Fig. 2 is an end elevation of the parts shown in Fig. 1.

Referring now to the drawing, in which like characters of reference designate similar parts, 10 designates a frame upon which is supported a box 11 for the reception of chalk or an equivalent. The bottom 12 of the box is raised by screws 13 to maintain 60 the chalk in contact with the rubberized surface of the fabric web 14 which passes over the open top of the box. The web is fed to the box by a roller 15 which is power driven by a belt pulley 16 or otherwise, there 65 being a roller 17 pivoted on the end of the frame as shown at 18, to bend the fabric over the roller 15 so that the latter can get a good purchase on the web. The chalked web is drawn off by a wind up device which 70 is about to be described, surplus chalk being scraped off the traveling web by scrapers 75 19—20 of the usual and well known kind.

In carrying out the invention, I attach 80 supporting brackets 21 to the frame 10, there being bearings 22 on the brackets to receive the shaft 23 of a driving roller 24 which is driven from a belt pulley 25 or otherwise. A pair of track rails 26 are fixed 85 to the brackets 21 outside of the driving roller and are inclined upwardly from the driving roller as shown. A pair of grooved wheels 27 ride on the track and form journals for the ends of a shaft 28 upon which a take-up roller 29 for the fabric is fixed, 90 there being ball bearings (not shown) in a ball race 30, between the shaft and wheels to permit the roller to turn freely in the 95 wheels.

The inclination of the track is sufficient 100 to maintain the take-up roller 29 in frictional contact with the driving roller so that the former is driven by the latter. As soon as a convolution of fabric is formed on the roller it will be driven by frictional engagement of the fabric with the driving roller, the weight of the roll of fabric as the convolutions increase, serving to supply sufficient pressure to smoothly and evenly lay the fabric on the roll. As the roll of fabric 105 increases in diameter the grooved wheels

- 27 are pushed outwardly and upwardly on the track, the inclination of which is such that the pressure of the outer convolution upon the inner convolution, caused by the 5 weight of the fabric roll upon the driving roll, will remain substantially the same regardless of the diameter of the fabric roll.
- In operation the fabric web is advanced progressively over the chalk box 11 and 10 wound up on the roller 29. As the roll of fabric increases in diameter on the take-up roller, the roll will be rotated at a proportionate decrease in speed so that the material will be always rolled up at a uniform 15 speed regardless of the size of the roll. Thus the tension on the fabric can not increase as the roll increases in diameter. Since the roll is permitted to move outwardly away from the driving roller as the 20 fabric convolutions accumulate, the pressure on the material from its own weight riding on the driving roller will be maintained substantially uniform so that at no time can

a sufficient degree of pressure be reached to squeeze out the chalk from between the convolutions of the fabric roll. 25

Having thus described my invention, what I claim as new and desire to protect by Letters Patent is:

In a machine of the character described 30 a trough open at the top for containing powdered material, a source of rubber-coated fabric supply, a reel for receiving the rubber coated fabric from the fabric supply source, means for guiding the fabric over the top 35 of the trough from the supply source to the reel, winding means for feeding the fabric across the trough, means adapted to raise the powdered material in the trough to maintain it in contact with the rubber-coated surface of said material, and means for removing the surplus powdered material 40 from the said rubber-coated surface.

Signed at Providence, Rhode Island, this 15th day of July, 1916.

JOSEPH T. BROGDEN.
